PAPERMAKER'S WET FELT

Howard M. Helland, Newfane, N.Y., assignor to
Lockport Felt Company, Inc., Newfane, N.Y.

Filed June 23, 1958, Ser. No. 743,624

7 Claims. (Cl. 28—78)

This invention relates to improvements in construction of papermaker's felts such as are used in the manufacture of paper, paper board, pulp, asbestos shingles, Transite pipes, and like products. For example, the invention relates generally to improvements in the art referred to in my previously filed application Serial No. 719,586, filed March 6, 1958.

It is a primary object of the present invention to provide for the papermaker's felt art specifically, an improved felt constructed of fibres, such as any of the conventionally used grades of wool, cotton, or other natural or synthetic fibres or combinations thereof; fabricated by means of a novel technique in this art so as to provide an improved papermaker's felt of many advantages.

A more specific object of the invention is to provide a felt as aforesaid which presents a working surface of improved smoothness and pulp supporting and cushioning characteristics.

Another object is to provide a felt aforesaid which is of improved efficiency as a drainage filter in its intended use.

Another object is to provide an improved felt as aforesaid which obtains maximum strength effects in the direction of the load.

Still another object of the invention is to provide a felt as aforesaid which also is of improved dimensional stability characteristics.

Another object is to provide an improved felt as aforesaid which is of such construction that whenever the load on the felt is relaxed the pores of the fabric tend to open, thereby facilitating cleaning of the felt.

Other objects and advantages of the invention will appear from the specification hereinafter, and the accompanying drawings, wherein:

Fig. 1 is a diagrammatic perspective view of one form of plied yarn such as may be employed in construction of a felt of the present invention;

Fig. 2 is a laterally distorted diagrammatic plan view (at reduced scale) of a swatch of fabric, illustrating the weave pattern employed in manufacture of the felt;

Fig. 3 is a diagrammatic plan view corresponding to Fig. 2 but of a swatch of the fabrication as it actually appears subsequent to initial weaving thereof; and

Fig. 4 is a diagrammatic fragmentary sectional view taken along line IV—IV of Fig. 3, but subsequent to final processing of the fabrication.

In the papermaker's wet felt art a prime desideratum is to provide a fabric structure which is longitudinally strong while at the same time comprising an efficient water-drainage or filter membrane in the form of a resilient mass. For such purposes the wool and/or other fibres used must be so integrated as to present to the pulp being treated a uniformly smooth and level yet resilient surface. The present invention provides the desired results through use of a novel fabrication of yarns wherein the individual fibres subsequent to the yarn interlocking operation are as free as possible to move rel-

2

ative to one another during the fabric "fulling" or milling operations.

Thus, the invention contemplates that the yarns be relatively interlocked in a novel manner in this art, so that when the yarns are worked into the fabrication the individual fibres thereof are under minimum constraint. This effect may be obtained by employing an interlock pattern involving only generally parallel warp yarns which are intertwined in novel manner. Preferably, at least a large percentage of these yarns will be of such form that the fibres thereof are substantially untwisted, as compared to conventionally twisted fibre yarns as are usually employed in this art. The yarns employed may be produced by either the so-called woolen system or any of the so-called worsted systems, and may be either "singles" or "plied" yarns. More specifically, the invention contemplates a felt fabrication comprising solely generally parallel yarns which are preferably of substantially untwisted form, so integrated during the fabrication process as to produce a novel felt construction wherein the relatively soft yarns are intertwined upon themselves so as to provide mutual mechanical reinforcements, thereby producing an overall strong fabric of improved "wet felt" characteristics, as will now be described in detail.

As a first step a singles yarn may be used. Or, in the alternative, a conventional "plied" yarn may be employed. Or, as still another alternative, as a separate operation, a plurality of singles yarns made with a minimum singles twist such as the pair of yarns 12—12 shown in Fig. 1 may be plied as by means of a neutralizing **Z** twist. Hence, the resultant plied yarn designated generally at 15 comprises intertwined singles yarns, the individual fibres 10 of which are as near as possible untwisted. By way of a specific example, the card roping may be initially drafted and **S** twisted at the rate of say 4.0 t.p.i. (twists per inch), according to the fibre lengths and other variables. The two singles yarns so produced may then be relatively entwined by means of a neutralizing **Z** twist in such manner as to provide a plied yarn of say 4.5 t.p.i. Experience indicates that approximately such a ratio of singles and plied yarn twists will result in production of a plied yarn as indicated at 15 in the drawing wherein the individual fibres are only very slightly twisted (in one direction or the other) or are substantially untwisted about their own axes, while gently winding spirally about the neutral axis of the yarn. In the alternative, the card roping may be formed into singles yarn stock by means of a **Z** twist operation, and the singles yarns may thereupon be **S** twisted into plied yarn form, to provide the plied yarn stock 15 as explained hereinabove. In either case the yarn stock may be described as comprising two groups of untwisted fibres gently rolling around one another. Due to the fact that the singles yarns are relatively entwined the overall structure of the plied yarns 15 has adequate strength to withstand the subsequent weaving operation, in spite of the fact that the individual fibres are substantially untwisted.

As the second phase of the manufacture of the fabric, pluralities of the yarns 15 are intertwined as shown in Fig. 2 wherein the construction is illustrated as when being laterally stretched out of natural condition to facilitate understanding of the nature of the yarn interweaving system. Thus, when the structure is relaxed to its normal condition as shown in Fig. 3, the yarns 15 are interlinked and nested together in a manner quite unique in the wet felt art. This fabric is then submitted to any suitable shrinking and "fulling" or "milling" operations; and thus the fabric is shrunk and "fulled" as into the form illustrated by Fig. 4. As shown in Fig. 3, the yarns 15 are substantially straightened out plan view

to their conditions of maximum efficiency with respect to resistance to tension loads on the felt. It will of course be understood that the fabric of the invention may be constructed by any suitable type machine.

Whereas, the yarns 15, due to their relatively entwined positions in the interlock pattern acquire optimum felt tension resistance characteristics, the locally soft nature of the yarn stock permit them to easily deform and bulk out and respond in improved manner to the fulling treatment because the individual fibres thereof are of improved mobility. Hence, in the resulting felt fabrication the fibres provide a mat of superior surface smoothness and cushioning characteristics. At the same time the double thickness and laterally unrestrained nature of the interlock pattern permits the fabric to "breathe" and to operate with maximum efficiency in accord with the phenomenon of capillarity and in response to the "pumping" action within the felt when passing through compression rolls; thereby improving its water removing abilities. For the same reason the fabric is of improved inherent self-cleaning characteristics and is more responsive to conventional cleaning devices than are felts of other construction. Thus, each fibre of the fabrication is disposed to act more efficiently in its assigned task.

By virtue of the present invention a wet felt of more open or coarser structure may be made to meet specifications heretofore met only by felts of finer construction. Yet, by reason of the more efficient bulking of the fibres in the felt of the invention, it is also of superior surface or "finish" characteristics. Hence, these new felts will be of superior drainage characteristics because the total felt weight may be lowered.

It is a particular feature of the invention that in the finished felt belt the individual yarns and fibres are disposed at only slightly oblique angles to the direction of belt travel (Fig. 3); thereby providing a felt of increased total load pulling power for the same felt weight, and avoiding "head-on" impacts of yarn "rises" or "floats" against stationary equipment such as suction boxes, cleaning shoes, etc.

It will of course be appreciated that the invention is not limited to the precise constructions illustrated herein nor to the specific wet felt usage described hereinabove, and that the construction may be modified without departing from the spirit of the invention or the scope of the appended claims.

I claim:

1. A new papermaker's felt for supporting and draining paper making material, said felt comprising a belt-like fabric structure having only substantially untwisted yarns running generally lengthwise of the belt each of said yarns following a slightly zig-zag course and hooking first around the next adjacent yarn at one side thereof and then around the next adjacent yarn at the opposite side thereof and so on throughout the length of the belt, the individual fibres of said yarns being spirally wound but substantially untwisted about their own axes, said yarns each comprising card roping twisted only slightly into twisted yarn form, said fabric being fulled.

2. A new papermaker's felt for supporting and draining paper making material, said felt comprising a belt-like fabric formed solely of relatively soft twisted yarns running lengthwise thereof each of said yarns following a slightly zig-zag course and hooking first around the next adjacent yarn at the opposite side thereof and so on throughout the length of the belt, the individual

fibres of said yarns being substantially untwisted about their own axes, said fabric being fulled.

3. A new papermaker's felt for supporting and draining paper making material, said felt comprising a belt-like structure having only substantially untwisted plied yarns running generally lengthwise thereof each of said yarns following a slightly zig-zag course and hooking first around the next adjacent yarn at the opposite side thereof and so on throughout the length of the belt, the individual fibres of said yarns being spirally wound but substantially untwisted about their own axes, said plied yarns each comprising a pair of singles yarns each comprising card roping twisted into conventional S twisted yarn form and Z twisted together in opposite direction into plied yarn form, said interlocked yarns being fulled.

4. A new papermaker's felt fabric for supporting and draining paper making material, said felt comprising a belt-like structure having relatively soft twisted plied yarns running lengthwise thereof each of said yarns following a slightly zig-zag course and hooking first around the next adjacent yarn at the opposite side thereof and so on throughout the length of the belt, the individual fibres of said yarns being substantially untwisted about their own axes, said yarns each comprising a pair of singles yarns twisted together into plied yarn form, said fabric being fulled.

5. A new papermaker's felt fabric for supporting and draining paper making material, said felt comprising a belt-like structure having relatively soft-twisted plied yarns running lengthwise thereof each of said yarns following a slightly zig-zag course and hooking first around the next adjacent yarn at the opposite side thereof and so on throughout the length of the belt, the individual fibres of said yarns being substantially untwisted about their own axes and each comprising a pair of singles yarns S twisted together into plied yarn form, each of said single yarns comprising card roping Z twisted in opposite direction into singles yarn form, said fabric being fulled.

6. A papermaker's felt for supporting and draining paper making material, said felt comprising a fabric structure having plied yarns running lengthwise thereof each of said yarns following a slightly zig-zag course and hooking first around the next adjacent yarn at the opposite side thereof and so on throughout the length of the belt, said yarns each comprising a plurality of singles yarns twisted together into plied yarn form, each of said singles yarns comprising card roping twisted into yarn form, said fabric being fulled.

7. A new papermaker's felt for supporting and draining paper making material, comprising a fabric structure having yarns running only lengthwise of the fabric each of said yarns following a slightly zig-zag course and hooking first around the next adjacent yarn at the opposite side thereof and so on throughout the length of the felt, each yarn being thereby interlocked alternately with the yarns oppositely adjacent thereto, said fabric being fulled.
